UNITED STATES PATENT OFFICE.

JAMES B. MILLER, OF ROCHESTER, NEW YORK, ASSIGNOR TO ROCHESTER CARRIER COMPANY, OF ROCHESTER, NEW YORK, A CORPORATION OF NEW YORK.

CELL-CASE AND BLANK THEREFOR.

1,157,712.

Specification of Letters Patent. Patented Oct. 26, 1915.

Application filed January 28, 1914. Serial No. 814,895.

To all whom it may concern:

Be it known that I, JAMES B. MILLER, a citizen of the United States, residing at Rochester, in the county of Monroe and 5 State of New York, have invented a new and Improved Cell-Case and Blank Therefor, of which the following is a specification.

My invention relates to cell-cases of the collapsible type and has reference, in the embodiment thereof shown in the accompanying drawings, to those adapted to use as receptacles for bottles or like articles; and the objects of the invention are, first, to provide an improved cell-case of the class 10 described; and, second, to provide a blank of such a conformation that the receptacle may be economically formed therefrom and with practically no waste of material. I attain these objects by making a cell-case or 15 carton as shown in the accompanying drawings, in which—

Figure 1 is a plan view of a blank from which a cell-case may be formed; Fig. 2, a front elevation of a completely formed case 20 in its collapsed condition; Fig. 3, a sectional view taken along the line $x-y$ of Fig. 1 but with the parts of the blank folded up; Fig. 4, a sectional view taken along the line x^1-y^1 of Fig. 6 with all parts above such 25 line removed; Fig. 5, a top end view of a cell-case showing the cover flaps in interlocking engagement; Fig. 6, a side view of a cell-case completely formed but with the cover members open; Fig. 7, a sectional view 30 similar to Fig. 4 but showing the case as partly collapsed; Fig. 8, a plan view of a modified form of blank; Fig. 9, a sectional view similar to Fig. 4 but of a cell-case formed from a blank such as seen in Fig. 8; 35 and Fig. 10, a sectional view similar to Figs. 4 and 9 but of a cell-case formed from a blank of still another modification, as will be explained.

Similar letters refer to similar parts 40 throughout the several views.

Referring first to Figs. 1 to 7, inclusive. In Fig. 1 there is shown a blank from which there may be formed a cell-case in accordance with my invention, the general 45 contour of which is substantially such as shown except that the contour will naturally be modified to meet the different forms

and proportions in which the completed case may be made. The blank is cut, as indicated, and is scored, on one side, along the dotted lines 1, 4, 5, 6, 7, 8, 9, 10, 11, 12 and 13, and, on the reverse side, along the dotted lines 2 and 3. The blank, then, comprises two rectangular, main body portions A and B, of equal size, flexibly connected along the score lines 10 and 12, respectively, to the centrally disposed portion C, which forms the bottom of the receptacle, and this member is foldable along its center on the score line 11. Outer cover flaps E and D, 55 adapted to interlock, are flexibly connected to the portions A and B along the score lines 9 and 13, such lines being parallel to the lines 10, 11 and 12. To the left, with reference to Fig. 1, of the portions A and B 60 and flexibly connected thereto along the score line 6—6 are two similar extensions T and T^1 , respectively, each of which is divided by the score lines 1, 2, 3, 4 and 5 into 65 six equal, parallel sections,—those of the extension T being lettered, from left to right, j , a^3 , h , a^2 , g and a^1 , while those of the extension T^1 are lettered, from left to right, j^1 , b^3 , h^1 , b^2 , g^1 and b^1 . To the right of the body portions A and B, and flexibly connected thereto along the score line 7—7, are 70 sections a and b , respectively, similar to the oppositely disposed sections a^1 and b^1 , and flexibly connected thereto along the score line 8 are attaching flaps f and f^1 , respectively. To the outer end of each section a , a^1 , b and b^1 there is flexibly connected an inner cover flap v . The cut out portion P of the blank between the extensions T and T^1 thereof is divided into halves, as shown, 75 and utilized for a purpose later to be explained.

In forming a cell-case from a blank which is cut out and scored as above indicated, cement is first applied to the sections h , h^1 , j and j^1 . Either of the extensions T or T^1 is then folded along the several score lines thereon with the sections thereof in the positions as indicated in Fig. 3 and the cemented parts pressed together to cause them to 80 firmly adhere. The other extension is folded up in like manner and the two half sections of the cell-case thus formed are brought together, as shown in Figs. 4 and 6,

while the parts forming the central wall or partition, consisting of the two pieces P which are used for this purpose, are properly cemented on both sides and placed between them.

- 5 A carton or cell-case having six cells compactly arranged in two parallel rows of three cells each is thus formed in which the body portions A and B of the blank are oppositely disposed outer walls connected at their ends by oppositely disposed outer walls comprising the sections $a-b$ and a^1-b^1 . The sections a^2 , a^3 , b^2 and b^3 form transverse partitions between the central wall or partition and the outer walls A and B, while the sections g , j , g^1 and j^1 become attaching members secured to the central wall P, and the sections h and h^1 attaching members secured to the walls A and B, respectively.
- 10 The member C forms the bottom of the receptacle, the inner cover flaps v are adapted to be folded down over the tops of the cells and the outer cover flaps are folded therewith over with the locking members e on the flap 15 E engaging in the slots d therefor in the flap D. The completely formed up case is collapsible and when in such condition the several parts assume the relative positions as seen in Figs. 2 and 7.
- 15 In forming a cell-case from a blank as shown in Fig. 1 and by using the cut out portion P between the extension members T and T^1 as the central wall or partition, there is practically no waste of material. However, without in any way departing from the spirit of my invention, a cell-case may be formed entirely from a single, one piece, blank such as is shown in Fig. 8 with its parts in straightened out relation and 20 formed up into a cell-case in Fig. 9. This blank is similar to that shown in Fig. 1 with the exception that the attaching flaps f and f^1 are dispensed with and the partition members F and F^1 are flexibly connected along 25 the line 8—8 to the side sections a and b , respectively.

The attaching sections g and j are secured to the member F and the similar sections g^1 and j^1 are likewise secured to the member F^1 , and these members F and F^1 are secured together to form a double central wall or partition. It will readily be seen that only one of the members F or F^1 need be provided, and in that event the sections g and j would be secured to one side of such member and the sections g^1 and j^1 to the other side thereof as is done when the separate partition P is used; and it will also be seen that the members F and F^1 could be flexibly connected to the sections j and j^1 , respectively, instead of to the sections a and b , but if so placed the attaching flaps f and f^1 would necessarily have to be provided also.

25 In Fig. 10 there is shown a carton having but a single row of cells and formed from

a blank such as shown in Fig. 1 but with the parts to the right and to the left of the side wall A removed and with a foldable bottom member C¹ only half the width of the bottom member C. The extension T¹ is folded as in Fig. 3 and the body portion or side wall A brought against and secured to the attaching sections g^1 and j^1 .

70 It is believed from the foregoing description of the blank and the modifications thereof with the method of forming up cell-cases therefrom that the method of using such receptacles is sufficiently clear to call for no further description herein.

75 What I claim is:

1. A blank for a cell-case comprising two rectangular side members, a foldable bottom member intermediate said side members and flexibly connected thereto, outer cover flaps flexibly connected to said side members opposite said bottom member, extension members flexibly connected to opposite sides of one of said side members, such extension members divided into flexibly connected parallel sections, and inner cover flaps flexibly connected to the outer ends of those sections of the extension members adjacent to 80 said side member.

85 2. A blank for a cell-case comprising two rectangular side members, a foldable bottom member intermediate said side members and flexibly connected thereto, outer cover flaps flexibly connected to said side members opposite said bottom member, extension members flexibly connected to opposite sides of one of said side members and similar extension members flexibly connected to opposite sides of the other one of said side members, such extension members divided into flexibly connected parallel sections, and inner cover flaps flexibly connected to the outer ends of those sections of the extension members adjacent to and on each side of 90 said side members.

95 3. A blank for a cell-case comprising two rectangular side members, a foldable bottom member intermediate said side members and flexibly connected thereto, outer cover flaps flexibly connected to said side members opposite said bottom member, extension members flexibly connected to opposite sides of each of said side members, such extension members divided into flexibly connected parallel sections, the outer most section of one of said extension members forming, when the 100 blank is formed into a cell-case, a central partition member, and inner cover flaps flexibly connected to the outer ends of those sections adjacent to and on each side of said side members.

105 4. A collapsible cell-case comprising the following parts formed from a single blank, viz.—two similar and oppositely disposed first side members, a foldable bottom member flexibly connected to said side members, 110

second side members flexibly connected to opposite sides of one of said first side members, attaching sections flexibly connected to said second side members adapted to be secured to the other one of said first side members, a series of flexibly connected sections flexibly connected to one of said attaching sections, such series comprising transverse partition sections and attaching sections, the section on one side of each transverse partition lying against and secured to one of said first side members and that on the other side thereof lying against and secured to the other first side member, inner cover flaps flexibly connected to the top edges of said second side members, and outer cover flaps flexibly connected to the top edges of said first side members.

5. A collapsible cell-case comprising the following parts formed from a single blank, viz.—two similar and oppositely disposed side members, a foldable bottom member flexibly connected to said side members, oppositely disposed side sections flexibly connected to each of said side members, a central partition member flexibly connected to one of said side sections, partition attaching sections flexibly connected to the remaining ones of said side sections, a series of flexibly connected parallel sections flexibly connected to one of said partition attaching sections on each side of said central partition, such series comprising transverse partition sections and attaching sections, the section 10 on one side of each transverse partition lying against and secured to one of said side members and that on the other side thereof lying against and secured to said central partition, inner cover flaps flexibly connected to the top edges of said side sections, and outer cover flaps flexibly connected to the top edges of said side members.

6. A collapsible cell-case comprising the following parts formed from a single blank, viz.—two similar and oppositely disposed side members, a foldable bottom member flexibly connected to said side members, oppositely disposed side sections flexibly connected to each of said side members, two central partition members flexibly connected to two of said side sections, said central partition members forming one central partition, partition attaching sections flexibly connected to the remaining two of said side sections, a series of flexibly connected parallel sections flexibly connected to one of said partition attaching sections on each side of said central partition, such series comprising transverse partition sections and attaching sections, the section on one side of each transverse partition lying against and secured to one of said side members and that on the other side thereof lying against and secured to said central partition, inner cover flaps flexibly connected to the top edges of

said side sections, and outer cover flaps flexibly connected to the top edges of said side members.

7. A collapsible cell-case comprising, in combination with a central partition, the following parts formed from a single blank, viz.—two similar and oppositely disposed rectangular side members, a foldable bottom member flexibly connected to said side members, oppositely disposed side sections flexibly connected to each of said side members, partition attaching sections flexibly connected to each of said side sections, a series of flexibly connected parallel sections flexibly connected to one of said partition attaching sections on each side of said central partition, such series comprising transverse partition sections and attaching sections, the section on one side of each transverse partition lying against and secured to one of said side members and that on the other side thereof lying against and secured to said central partition, inner cover flaps flexibly connected to the top edges of said side sections, and outer cover flaps flexibly connected to the top edges of said side members.

8. A collapsible cell-case comprising, in combination with a central partition, two similar half portions each having a side member, similar side sections flexibly connected to opposite sides of said side member, a series of flexibly connected sections flexibly connected to said side sections and folded to form a row of cells, said series comprising transverse partition sections and attaching sections, the section on one side of each transverse partition lying against and secured to said side member and that on the other side thereof lying against and secured to said central partition; a foldable bottom member flexibly connecting the side members of said half portions, inner cover flaps flexibly connected to the top edges of said side sections, and outer cover flaps flexibly connected to the top edges of said side members.

9. A collapsible cell-case comprising, in combination, a central partition, two oppositely disposed main side members connected by two oppositely disposed foldable side members each comprising two side sections, attaching sections flexibly connected to cooperating ones of said side sections and secured to opposite sides of said central partition, transverse partition sections on each side of said central partition and means for flexibly connecting said transverse partition sections to said central partition and to said main side members, a foldable bottom member flexibly connected to said main side members, inner cover flaps flexibly connected to the top edges of said side sections, and outer cover flaps flexibly connected to the top edges of said main side members.

10. A collapsible cell-case comprising, in combination, two oppositely disposed main

- side members, a foldable bottom member flexibly connected to said side members, a centrally disposed partition member, a member flexibly connected to opposite edges of each 5 of said side members and secured to the central partition member near the outer edges of said partition and also secured, intermediate said attachments, to the inner face of its respective main side member thus forming 10 oppositely disposed foldable side members and transverse partition members, outer cover flaps flexibly connected to the top edges of said main side members, and inner cover flaps flexibly connected to the top edges 15 of said foldable side members.
11. A collapsible cell case comprising the following integral parts formed from a single blank, viz., two similar and oppositely disposed main side members, a foldable bottom member flexibly connected to and located between said side members, second side members flexibly connected to opposite sides of one of said main side members, attaching 20

sections flexibly connected to said second side members, and a series of flexibly connected sections flexibly connected to one of said second side members. 25

12. A collapsible cell case comprising the following integral parts formed from a single blank namely, viz., two similar and oppositely disposed main side members, a foldable bottom member flexibly connected to and located between said side members, second side members flexibly connected to opposite sides of one of said main side members, a series of flexibly connected sections 30 flexibly connected to one of said second side members, said series comprising alternate transverse partition sections and attaching sections, the attaching sections being parallel with the main side members and attached thereto when in contact therewith. 35

JAMES B. MILLER.
